(57) **CLAIM**

The ornamental design for a boat light, as shown and described.

DESCRIPTION

FIG. 1 is a perspective view of a boat light, showing our design;

FIG. 2 is an elevational view of one side;

FIG. 3 is a front elevational view;

FIG. 4 is a rear elevational view;

FIG. 5 is a top view; and,

FIG. 6 is a bottom view.

The other side is a mirror image of FIG. 2.
